UNITED STATES PATENT OFFICE.

CHARLES L. ELMQUIST, OF ST. PAUL, MINNESOTA.

DESIGN FOR A TALKING-MACHINE CABINET.

55,989.

Specification for Design.

Patented Aug. 10, 1920.

Application filed June 23, 1919. Serial No. 306,276. Term of patent 14 years.

To all whom it may concern:

Be it known that I, CHARLES L. ELMQUIST, a citizen of the United States, residing in St. Paul, in the county of Ramsey and State of Minnesota, have invented a new, original, and ornamental Design for Talking-Machine Cabinets, of which the following is a specification, reference being had to the accompanying drawing, forming part thereof.

The drawing shows a front elevation of my improved talking machine cabinet.

I claim:

The ornamental design for a talking machine cabinet as shown.

In testimony whereof I affix my signature in presence of two witnesses.

CHARLES L. ELMQUIST.

Witnesses:

CARL D. SWENDSON,
DEBORAH BRYAN.
